UNITED STATES PATENT OFFICE.

JOHN STORER, OF MARLBOROUGH, NEW YORK.

FURNACE-GRAVE.

SPECIFICATION forming part of Letters Patent No. 324,966, dated August 25, 1885.

Application filed November 6, 1884. (No model.)

To all whom it may concern:

Be it known that I, JOHN STORER, a citizen of the United States, residing at Marlborough, in the county of Ulster and State of New York, have invented new and useful Improvements in Furnace-Grates, of which the following is a specification.

This invention consists in the combination, with a furnace-grate and with the ash-pit situated beneath the grate, of a trap-door which leads from the fire-chamber into the ash-pit, so that when the trap-door is opened by swinging it upward and outward it serves as a support for a rake, so that the ashes, as the same accumulate on the grate, can be raked down into the ash-pit, while the door of the ash-pit remains firmly closed in order to prevent the escape of dust. The trap-door is by preference situated between the front ends of the grate-bars and the furnace-door, so that it can be conveniently raised when the furnace-door is opened. A suitable spring-catch retains the door in its raised position, and in the ash-pit is placed a sprinkler for the purpose of laying the dust during the operation of dumping the ashes from the fire-chamber into the ash-pit.

In the accompanying drawings, Figure 1 represents a longitudinal vertical section. Fig. 2 is a transverse section in the plane $x x$, Fig. 1.

Similar letters indicate corresponding parts.

In these drawings the letter A designates the fire-chamber. B is the door leading into the fire-chamber. C is the ash-pit, and D the door leading into the ash-pit. On the bottom of the fire-chamber are placed the grate-bars E, and between the front ends of the grate-bars and the furnace-door B is situated a trap-door, F, which leads down into the ash-pit. This trap-door swings on hinges a , and it opens upward and outward toward the furnace-door B, so that when it is thrown open it occupies the position shown in the drawings. In the trap-door F is a hole, b, so that when the furnace-door B is opened a poker or other instrument can be inserted into said hole and the trap-door can be opened. On the trap-door is secured a spring-catch, c, which, when said door is opened, engages with a lug, d, so as to retain the door in its

open position. The outer end of the spring-catch c connects by a chain, e, with a rod, f, which is provided with a handle, g, and which slides in the front plate, G, of the furnace. A 55 spring, h, has a tendency to force the rod f inward, in order to keep the handle g as much as possible out of the way. On the interior of the front plate, G, beneath the bottom of the fire chamber, is situated a sprinkler, H, 60 which is supplied with water under pressure by means of a pipe, I. The ash-pit door D is provided with a hole, i, into which is fitted the handle of a rake, J.

When the fireman desires to rake out the 65 ashes from the fire-chamber, he opens the trap-door F, and as the same is retained in its open position by the spring-catch c, it forms a support for the rake which serves to rake the ashes out through the opening of the trap-door. The ash-pit door is firmly closed, and as the ashes are being dumped into the ash-pit they are exposed to a spray of water issuing from the sprinkler H, so that they are cooled off, and at the same time the dust is 70 laid. As the ashes accumulate in the front portion of the ash-pit they are pushed back by means of the rake J, which can be operated without opening the door of the ash-pit. By these means the fireman is enabled to discharge the ashes from the fire-chamber without permitting any dust to escape from the furnace, which is a great desideratum in places where the furnace is put up in a room part of which is occupied as a store-room. 80

By pulling the handle g outward the spring-catch c is thrown out of gear with the lug d and the trap-door is closed.

The handle of the rake J is by preference made in sections, for the purpose of facilitating the operation of putting said rake in position.

I am aware that it is not new to arrange a drop-plate in front of the grate-bars of a furnace, so that such plate can be swung downward to permit the ashes to be drawn through the opening into the ash-pit. My invention differs therefrom in that my trap-door is so hinged that it can swing upward and outward to an upright position in front of the grate, 95 and thereby subserve the function of a support for the rake in its reciprocations to draw

the ashes through the trap-door opening. I am also aware that it is not broadly new to throw jets of water into the ash-pits of furnaces; but such I do not broadly claim.

5 What I claim as new, and desire to secure by Letters Patent, is—

1. The combination, with a furnace-grate and an ash-pit below the same, of a trap-door arranged in front of the grate-bars and hinged 10 to swing upward and outward to an upright position and constitute a support for the rake to draw the ashes through the opening of the trap-door, substantially as described.

2. The combination, with a furnace-grate 15 and an ash-pit beneath the same, of a trap-door hinged to swing upward and outward to an upright position and constitute a support for the rake to draw the ashes through the trap-door opening, and a spring-catch for sus- 20 taining the trap-door in its upright position, substantially as described.

3. The combination, with a furnace-grate and an ash-pit below the same, of a trap-door hinged to swing upward and outward to an 25 upright position in front of the grate and con-

stitute a support for a rake to draw the ashes through the trap-door opening, a spring-catch carried by the trap-door for holding the latter in its upright position, and a handle outside the furnace and connected with the spring- 30 catch for releasing the same to close the trap-door, substantially as described.

4. The combination, with a furnace-grate and an ash-pit below the same, of the trap-door hinged to swing upward and outward to 35 an upright position in front of the grate and constitute a support for a rake to draw the ashes through the trap-door opening, a sprinkler, H, arranged adjacent to the front plate of the furnace beneath the trap-door 40 opening, and a pipe, I, for delivering water to the sprinkler, substantially as described.

In testimony whereof I have hereunto set my hand and seal in the presence of two sub-scribing witnesses.

JOHN STORER. [L. S.]
